United States Patent Office

Des. 205,324
Patented July 19, 1966

205,324

CASING FOR A CALCULATING MACHINE OR SIMILAR ARTICLE

Richard Hollerith, Jr., Upper Montclair, and Terry L. Barner, Orange, N.J., assignors to Monroe International Corporation, Orange, N.J., a corporation of Delaware

Filed June 17, 1965, Ser. No. 85,789

Term of patent 14 years

(Cl. D64—11)

FIG. 1

FIG. 2

FIG. 3

FIG. 4

FIG. 1 is a front perspective view of a casing for a calculating machine or similar article;

FIG. 2 is a right side elevational view thereof;

FIG. 3 is a rear elevational view thereof; and

FIG. 4 is a top plan view thereof.

The broken line showing of the keys, etc., is for illustrative purposes only.

We claim:

The ornamental design for a casing for a calculating machine or similar article, substantially as shown and described.
